BORING BAR

Phillip A. Vonada, Dayton, Ohio

Application June 8, 1944, Serial No. 539,369

3 Claims. (Cl. 82—36)

(Granted under the act of March 3, 1883, as amended April 30, 1928; 370 O. G. 757)

The invention described herein may be manufactured and used by or for the Government for governmental purposes, without the payment to me of any royalty thereon.

The present invention relates to cutting bar holders for metal working machines.

Both in boring and turning, as well as in other similar types of metal cutting machines, there is difficulty, especially in the heavy duty class of machine, in providing a sufficiently firm or solid foundation or base as a tool holder. A further difficulty is in adequately supporting the cutting end of the tool when cutting on relatively large diameters. In boring, for instance, the holder for the cutting bar is disposed at the approximate center of the circle of the cut and the cutter bar terminating in the cutter blade extends in a generally radial direction from the holder to the surface being cut. On small diameter work the length of bar, from holder to cut, is relatively short, with corresponding small leverage. As the diameter increases, the length of bar increases and the leverage is increased in proportion. As the leverage increases, the yield of the bar, under stress of the cut, tends to produce irregularities, inaccuracies or imperfections in the work. This is serious enough in the rough cuts but in the final cuts is not permissible. Accordingly, there are definite recognized limits to the length of cutting bar between its support and the surface being cut. Of course, the resistance of the bar may be increased by increasing its width and thickness dimensions relative to its length, but there are definite recognized limits beyond which that policy is not practicable.

The present invention meets and overcomes the above and other objections and provides a simple, efficient and compact cutting tool holder adequately bracing the cutter bar for a wide range of diameters of cuts.

In order to more clearly disclose the construction, operation and use of the invention, reference should be had to the accompanying drawing forming part of the present application. Throughout the different figures of the drawing, like reference characters designate the same parts in the different views.

In the drawing:

Fig. 1 is a top plan view of the invention;

Fig. 2 is a front elevation of the clamping block, with the machine bed guide indicated;

Fig. 3 is a perspective view of lower half of block of Fig. 1;

Fig. 4 is a top plan view of a tool supporting rod;

Fig. 5 is a front view of a collet adapted to be mounted in the block of Fig. 2; and

Fig. 6 is a side elevation of Fig. 5.

Referring to the drawing in detail, 1 indicates the lower and 2 the upper block of the clamp member for securing the tool holding rods. This clamp is provided with cooperating rod seats 3 in its respective upper and lower members adapted to be aligned and when so aligned, to receive or securely seat therein tool holding or cutting bar supporting rods 4. It is clamped in operative position about rods 4 by a threaded post 5 passed vertically through the approximate center of the assembled blocks and provided with a collar 6 adapted to engage the lower face of the lower block 1. By tightening nut 7, the blocks 1 and 2 may be clamped tightly together thereby securing the rods 4 in place in seats 3.

As a simple means of quickly and accurately 20 guiding blocks 1 and 2 to aligned or clamping position, small spring pressed guiding plungers 8 are provided along the approximate longitudinal center line of the lower block 1 adapted to register with and seat in corresponding sockets 9 25 in the upper block 2. These plungers, in operative positions, are indicated, in dotted line, in Fig. 2. Each is provided with a collar 10 having free movement in an enlarged bore 11 communicating with the smaller bore through which the plunger 30 extends to seat in socket 9. The lower end of this larger bore is closed by a threaded plug or nut 12 between which and collar 10 is confined coil spring 13, continually exerting pressure to yieldingly maintain plungers 8 in operative guiding 35 positions.

Threaded post 5 extends through the approximate center of the assembled blocks 1 and 2 and is adapted to be and intended to be mounted on the machine bed in the same approximate position 40 as the regular standard tool holder. As is well-known, such holders are provided with suitable means for advancing them toward or from their work, along the bed or way of the respective machine and, when desired, securing them in selected 45 adjusted positions. Usually, in turning or boring operations, to which this invention is applicable, the tool holder is automatically fed, relatively to the work being done. The type of machine, the relative position of the tool holder thereon, the mounting of the tool holder on the machine and various types of mechanism for feeding the tool holder are all well known to every one skilled in the art to which this invention relates and, accordingly, need not be either illustrated or described here. The guides or way 14 of the ma-

chine are shown in cross section, including a fragment of the machine bed in which the way is formed.

By having a block of considerable width extending proportionately on either side of the center of the post 5 and longitudinal center of way 14, and providing that block with rod seats 3 at both sides of that center, laterally spaced tool bar supporting rods 4 may be firmly seated in the block. That, in turn, makes it possible to mount the tool bar supporting rod 4 at a considerably greater distance radially of the cut from the post 5 toward the work than is possible without this invention. That, alone, would not sufficiently counteract the increased leverage, although some of that leverage would be taken up by the supporting bar and clamp.

In order to get the greatest practicable bracing effect against or offsetting the extended cutting bar and enable the cutting end of the bar to be projected or extended radially from post 5 to take full advantage of this invention, two parallel rods 4 are used, both securely clamped between blocks 1 and 2. Each of these rods is provided with a bore or passage 15 extending centrally through it, diagonally at an angle of about 45° to its lateral cross section and a short distance from one end. The bores here shown are to receive tool bars of approximate square cross section and, therefore, are of like cross section. For tool bars of different cross section, the bore 15 would be of correspondingly different shape. To securely lock the tool bar in its supporting rod 4 suitable set screws or the like are used, the respective rod end being cut off diagonally or in a plane parallel with 15 and slightly spaced therefrom to provide a plane surface for the binding screws. In use, the rods 4 are seated in the clamp between blocks 1 and 2 with their respective bores 15 aligned, as shown in Fig. 1. Then the tool bar 16 is seated in both aligned bores of the rods 4, moved to the desired position to make the required cut and positively locked in that position by the set screws. Then the nut is tightened on 5 solidly clamping rods 4 in place, with their tool bar 16. The guide plate 17, of post 5, as will be well understood, plays freely in the way 14 of the machine for usual adjustments, being secured in any such adjusted position by the bolts 14'. The two parallel rods 4 provide a wide-base, firm, bracing support for tool bar 16 completely offsetting most of the leverage otherwise imposed upon it for a considerable range of diameters beyond what would be the maximum where the tool bar is supported by a post having the approximate position of post 5.

In combination with the clamping block, where smaller tool holders and cutting tools are to be used, a collet type adapted (Figs. 5 and 6) is provided. The collet type holder here shown comprises a split tube 18 having a friction grip hold or clutch action and having an external over-all diameter very slightly greater than the over-all internal diameter of the bores formed between the blocks 1 and 2 when assembled in operative position. The free end is headed as at 19 and knurled to provide easy handling and positioning and to act as a stop when placing in the clamp. With such a collet holder in position, tightening of the nut on post 5 will compress 18 sufficiently to grip tightly the rod 4 seated in the tube.

A very important and novel feature of this collet holder is the position of its longitudinal bore 20 which receives rod 4. That bore is not

concentric with the longitudinal axis but eccentric. The degree of eccentricity is variable and may be greater in one than in another. Likewise bores 20 may be of different diameters. It will be obvious that, assuming two such collet type holders clamped in position in the same way that rods 4 have been described as clamped and each carrying a rod 4 clamped therein, the rods being so placed that bores 15 thereof are aligned, a cutting tool bar 16 may be seated in and supported by those rods in the same way as hereinabove disclosed. A much smaller cutting bar, with correspondingly smaller supporting rods may be used by this assembly.

The eccentric position of bores 20 provides for a considerable range of adjustments of the supporting rods 4. Each collet holder may be rotated to carry its bore 20 and the corresponding rod 4 to any one of a wide range of positions around or eccentric to the longitudinal center or axis of the collet. The pair of collets thus adjusted provide corresponding adjustment of the cutting tool relatively to the work.

It will be well understood that a single collet type holder, with rod 4 and tool bar may be used, if desired under proper conditions. In that case, the eccentric bore of the collet gives a considerable range of adjustments of the cutter bar impossible in other holders—i. e. adjustments around 30 and relative to the longitudinal axis of the collet or of the corresponding bore between blocks 1 and 2.

Although the bores 15 have been shown as diagonal and disposed at an angle of about 45°, it will be understood that the invention is not in any degree limited to such angular disposition. That is a preferred arrangement. The bore 15 may be disposed radially of bars 4 or at angles between the radius and the 45° angle, according 40 to the work to be done and other well known controlling factors.

It is thought that the construction, operation and use of the invention will be clear from the preceding detailed description.

Many changes may be made in the construction, arrangement and disposition of the several parts of the invention within the scope of the appended claims without departing from the field of the invention and it is meant to include all such within this application wherein only one preferred construction and arrangement and one modification thereof have been disclosed purely by way of illustration and with no thought or intent of limiting the claims thereby, and it is 55 meant to include all such within this application.

Having thus described my invention what I claim and desire to protect by Letters Patent is:

1. In combination, a pair of clamping blocks provided with spaced parallel rod-receiving seats, 60 the seats of one block being adapted to be aligned with those of the other one of said blocks being provided with guide pin sockets in its inner face while the other is provided with bores of corresponding diameter alignable therewith and bores 65 of greater diameter concentric with the first bores said bores together extending completely through the respective block, plungers freely movable in said bores and, in operative position, extending into said sockets, said plungers carrying 70 heads of increased diameter movable in the bores of greater diameter, threaded plug closures for said larger diameter bores, compression coil springs confined between said plug and said head, means disposed centrally of the aforesaid blocks 75 approximately midway between the seats thereof

for securing said blocks to the guide-way of a metal working machine, rods mounted in the aforesaid seats and provided with aligned cutter bar openings therethrough disposed at an angle to the width of said rods and means for clamping the aforesaid blocks in rod securing position.

2. In combination, a lower clamping block provided with parallel spaced rod-receiving seats and centrally disposed yielding guide plungers, an upper cooperating block having cooperating complementary rod-receiving seats adapted to be guided to operative position by said plungers, a pair of cutter bar receiving rods disposed in said seats between said blocks, and provided with aligned cutter bar receiving openings therethrough disposed at an angle to the width of the

rod, a single cutter extending through the aligned openings in said rods and means for securing said blocks in operative position on the guide-way of a machine.

5 3. In combination, a lower clamping block provided with parallel spaced rod-receiving seats, an upper cooperating block having cooperating complementary rod-receiving seats, a pair of tubular clamping members seated between said blocks in said seats and provided with eccentrically disposed longitudinally extending rod receiving bores, rods clamped in said bores and provided with aligned cutter bar receiving openings, and a single cutter bar seated in said aligned openings.
